UNITED STATES PATENT OFFICE.

RICHARD F. BEAMER, OF SAN FRANCISCO, CALIFORNIA.

WOODEN GOLF-CLUB.

1,359,220.

Specification of Letters Patent. Patented Nov. 16, 1920.

Application filed May 22, 1919. Serial No. 298,913.

To all whom it may concern:

Be it known that I, RICHARD F. BEAMER, a citizen of the United States, and a resident of the city and county of San Francisco and 5 State of California, have invented a certain new and useful Wooden Golf-Club, of which the following is a specification.

The invention relates to wooden golf clubs.

An object of the invention is to provide a 10 wooden golf club, which, with the same applied force, will drive a golf ball farther than the ordinary wooden-faced clubs.

Another object of the invention is to provide a wooden golf club having a resilient 15 driving face having substantially the same period of vibration as the golf ball.

When a body is strained within the elastic limit, the internal stresses tend to restore the body to its original condition. When released from the external deforming force, 20 the body vibrates, and, since the restoring forces are at each stage proportional to the distortion, the vibrations are simple harmonic vibrations of a constant period.

25 When a golf ball is struck, it is deformed and in regaining its original shape, it vibrates in simple, harmonic vibrations of a constant period. In accordance with my invention, I provide a wooden golf club having 30 an elastic or resilient face, which when struck, vibrates in simple harmonic vibrations of the same or substantially the same constant period as the golf ball. The restoring stresses, therefore, of both the golf 35 ball and the driving face, combine to drive the golf ball from the club.

The invention possesses other advantageous features, some of which, with the foregoing, will be set forth at length in the following description, where I shall outline in full, those embodiments of my invention which I have selected for illustration in the drawings accompanying and forming part of the present specification.

45 Referring to said drawings:

Figure 1 is a front view of the head of a driver embodying my invention.

Fig. 2 is a longitudinal section through the driver shown in Fig. 1.

50 Fig. 3 is a front view of the head of a driver showing a modified form of the invention.

Fig. 4 is a vertical transverse section 55 through a driver head showing a further modified form.

Fig. 5 is a horizontal section through a driver head showing another modified form.

In accordance with my invention, I provide a driving surface on the face 2 of the head, which has substantially the same period of vibration as the golf ball. This surface is preferably formed of a steel plate 3, of such resiliency and elasticity that when struck, it vibrates in time with the vibrations of the ball, so that the rebound of the 60 plate is simultaneous with the rebound of the ball. The plate 3 is preferably made of spring steel or saw blade steel of the necessary thickness in proportion to its area to vibrate at the required frequency. In Fig. 70 1, the plate 3 is substantially rectangular in shape and is provided with backwardly directed walls 4, which are provided on their ends with flanges 5, through which screws are passed, to secure the plate to the head. 75 The head 6 is provided with a recess 12 in its front face, and the plate is set in the recess with the face of the plate flush with the face of the head. This provides an open space between the plate and the rear wall 7 80 of the recess so that the plate is free to vibrate in its natural period. The spaces between the side walls 4 and the sides of the recess are filled with hard rubber 8 or similar material, so that no edges or corners are 85 presented on the face of the head.

In the construction shown in Fig. 3, the plate 3 is circular and seats in a cylindrical recess in the head, the space between the side walls and the wall of the recess being filled 90 with material 8.

In the construction shown in Fig. 4, the upper and lower faces of the head are countersunk slightly behind the recess 12 and the plate 3, instead of being provided with side 95 walls, is provided with top and bottom walls 13 which seat in the countersunk portions. The plate is of the same width as the recess, so that it closes the front of the recess entirely, while allowing the plate to vibrate 100 freely, both by the flexing of the plate and the flexing of the walls.

The construction shown in Fig. 5 is similar to that shown in Fig. 2, with the exception that the vibratory element, instead of 105 being formed of one plate, is formed of a plurality of plates 14, producing a laminated structure.

The striking plate in all instances is spaced from the back of the recess and 110

nothing is inserted between the plate and the back of the recess, so that the plate has a free natural period of vibration, which is chosen so as to be the same or substantially the same as that of the golf ball.

I claim:

1. A golf club provided with a wooden head having a recess in its face, a metallic striking plate fitted into said recess and lying flush with said face, and walls extending backwardly from the edges of said face and secured to the bottom of the recess in said head, the plate being spaced from the rear wall of the depression so that it is free to vibrate in its natural period.
2. A golf club having a solid head with a recessed front face, a resilient striking plate having rearwardly extending flanges with

out-turned lips, and means passing through said lips to secure the plate in the recess and flush with said face.

3. A golf club having a solid head with a recessed front face, a resilient striking plate having rearwardly extending flanges with out-turned lips, means passing through said lips to secure the plate in the recess and flush with said face, and a filling, between said flanges and the walls of the recess, covering the securing means.

In testimony whereof, I have hereunto set my hand at San Francisco, California, this 15th day of May 1919.

RICHARD F. BEAMER.

In presence of—
H. G. PROST.
